UNITED STATES PATENT OFFICE.

FRANK B. LINDOW, OF MILWAUKEE, WISCONSIN,

DESIGN FOR A DESK LAMP.

Application filed January 10, 1923. Serial No. 4,858. Term of patent 3½ years.

To all whom it may concern:

Be it known that I, FRANK B. LINDOW, a citizen of Germany, residing at Milwaukee, in the county of Milwaukee and State of Wisconsin, have invented new, original, and ornamental Design for Desk Lamps, of which the following is a specification, reference being had to the accompanying drawing, forming part thereof.

The drawing is a perspective view of a desk lamp embodying my new design.

The base of the lamp comprises a shell, from the forward part of which arises the rearwardly inclined body of a mermaid who supports a water lily which provides a socket for the lamp bulb, shown in dotted lines.

I claim:

The ornamental design for a desk lamp, as shown and described.

FRANK B. LINDOW.
